UNITED STATES PATENT OFFICE.

JOSEPH S. THOMAS, OF GREENVILLE, MISSISSIPPI.

METHOD OF MAKING SHOES.

1,130,859.

Specification of Letters Patent. Patented Mar. 9, 1915.

Application filed October 31, 1913. Serial No. 798,605.

To all whom it may concern:

Be it known that I, JOSEPH S. THOMAS, a citizen of the United States, residing at Greenville, in the county of Washington 5 and State of Mississippi, have invented certain new and useful Improvements in Methods of Making Shoes, of which the following is a specification.

This invention relates to improvements in 10 the art of making foot gear, as for instance shoes, slippers, and the like.

It is one of the objects of this invention to provide an improved method whereby the body of a slipper or shoe may be formed of 15 flexible, soft cord wound about a last in such a manner as to dispose the winds of the cord in lateral abutting relation whereby the entire exterior body of the shoe will be formed of cord.

20 A further feature of the method consists in forming a shoe body of a single length of cord and anchoring an intermediate portion of the cord upon one part of the last and then successively winding the opposite ends 25 of the cord about the last, in opposite directions, to form a shoe body.

A further object is to provide an improved method whereby the winds are not only stitched in lateral abutting relation but 30 to a soft lining as each successive wind is positioned about the last.

My improved method will be more fully described in connection with the accompanying drawing and will be more particularly 35 pointed out and ascertained in and by the appended claims.

In the drawings:—Figure 1 is a perspective view of a last illustrating the method of forming a shoe or slipper thereon in accordance with my invention. Fig. 2 is a side view of a completed article. Fig. 3 is an inside view illustrating the appearance of the lining and the manner in which the same is secured to the cord body. Fig. 4 is a trans- 45 verse sectional view across the ball portion of the foot gear illustrating the exterior and interior appearance of the same.

Like characters of reference designate similar parts throughout the different figures of the drawing.

50 As illustrated, 1 designates a last upon which the lining 2 is first fitted. The lining 2 will preferably be of a soft fabric or flannel and may be held on the last by a line of stitching 3, as shown. Separate portions of the lining may be provided to form the

counters 4 and heel portion 5. After the lining is fitted on the last I wind about the covered last a soft flexible cord in such close relation that the winds abut in lateral relation so as to completely form a shoe or slipper body and wholly cover the lining. 60

In the most improved form of my method I preferably utilize a single length of cord and attach an intermediate portion of such 65 length of cord to one part of the last, at the desired starting point. I have found it advantageous to start at the crown or tip of the vamp, as indicated at 6, to which part I may tack or otherwise secure the intermediate portion of a length of cord. The first wind will be from anchorage point 6 downwardly on the left side of the last and under the same at approximately the juncture of the shank with the ball portion of the sole. 70 This first wind will appear at 7 at the right of Fig. 1, and will be completed by being extended up to starting point 6. The wind toward the toe will be taken up from end portion *a* of the cord whereas the winds toward 75 the heel will be taken up from end portion *b* of the cord. The first wind may be tacked or otherwise secured so as to prevent the same from slipping and as the next adjacent wind is completed, the two winds may be 80 stitched in abutting relation with respect to each other and, in the most improved form of the method, to the lining 2, so as to hold the cords in place. In Fig. 1 I have illustrated short lines of stitching 8 whereby the 85 last two winds are stitched together in lateral abutting relation with respect to each other, the stitching 8 being extended through the lining 2 as indicated in Fig. 3. I may also stitch the winds as indicated at 9 so 90 that adjacent winds of alternate pairs may be connected. By advancing the toe winds as regards the lower portions with respect to the upper portions thereof, the final wind will be on top of the toe portion so as to permit of the same being readily finished off. 95 It will be readily seen from the foregoing that as the winds are continued, from the partial showing in Fig. 1, that the lining 2 will be completely covered to form a cord 100 shoe body as indicated in the finished form shown in Fig. 2.

The first wind of cord *b* toward the heel end of the shoe body, is indicated at 10 and extends about the counters 4 along the right side of the last and round to the left side thereof up to the point *x*, where the first 110

wind 10 will extend downwardly in lateral abutting relation with the first wind of the toe end *a* from the point 6. Thus the first wind 10 of the heel end *b* will appear on the 5 right side of the last at 11 where it will follow the first wind of the toe end up to a point approximately indicated by *x*, where it will turn downwardly, as indicated at 12, and follow the first wind 10. Stitching 13 10 will secure the first wind around the heel end in lateral abutting relation and the winding will continue until the heel end is covered.

The stitching of the cord to the lining is 15 indicated in the transverse section shown in Fig. 4 wherein the lining is indicated at 2, and the stitching at 8. The twine which is used in stitching the cord to the lining will be of soft material and it will be stitched 20 into the lining in such a manner to almost completely embed itself so that the interior of the slipper or shoe will present a smooth soft surface to the foot.

In the finished article as shown in Fig. 2, 25 a sole 14 and a heel 15 will be attached in any desirable manner but I desire it to be understood that in some utilities of the invention, for instance as a house slipper, it may consist wholly of the cord and the lining and the sole and heel may be omitted.

The stitching has been shown in exaggerated spaced relation for clearness of illustration.

It is believed that the method of my invention has been fully disclosed in the foregoing description so that the advantages and utilities will be clearly understood, and while I have herein shown and described one specific form of the invention, I do not wish 40 to be limited thereto except for such limitations as the claims may import.

I claim:—

1. The herein described method of forming a shoe which comprises mounting a lining over a last, winding cord over the lining, and securing the cord to the lining.

2. The herein described method of forming a shoe body which comprises mounting a lining over a last, winding cord about the 50 last and over the lining, and securing each strand of cord to said lining as the winding progresses.

3. The herein described method of forming a shoe body which comprises securing a lining upon a last, winding cord about the lining to dispose the winds in lateral abutting relation and cover the lining, and stitching the cords to each other and to the lining.

4. The herein described method of forming a shoe body which comprises fitting a lining to a last, winding cord about the last

with the winds in a lateral abutting relation to cover the lining, and successively stitching the winds to each other and to the lining 65 as the cord is being wound.

5. The herein described method of forming a shoe body which comprises anchoring a single length of cord to one portion of a last, winding one end portion of the cord 70 around the last in one direction, and winding the other end portion of the cord around the last in another direction.

6. The herein described method of forming a shoe body which comprises anchoring 75 an intermediate portion of a single length of cord to the crown or tip of the vamp of a last, winding one end of the cord about the last toward the toe portion in one direction, and winding the other end portion of the 80 cord about the last toward the heel portion.

7. The herein described method of forming a shoe body which comprises fitting a lining on a last, anchoring an intermediate portion of a cord at one point upon the last, 85 winding one end of a cord about the lining to cover the same with the winds extending in one direction, and winding the other end portion of the cord about the lining with the winds extending in another direction. 90

8. The method of forming a shoe which comprises shaping a single length of cord over a last by winding the two ends thereof in opposite directions around the last.

9. The herein described method of forming a shoe body which comprises fitting a lining on a last, placing an intermediate portion of a length of cord at a predetermined point upon the last, winding one end of the cord about the lining to cover the 100 same with the winds extending in one direction, winding the opposite end portion of the cord about the lining with the winds extending in another direction, and securing the winds to each other and to the lining. 105

10. The herein described method of forming a shoe body which comprises fitting a lining upon a last, placing an intermediate portion of a cord at a predetermined point upon the lining as it covers the last, winding 110 one end of the cord about the lining to cover the same with the winds extending in one direction, winding the remaining end portion of the cord about the lining with the winds extending in the opposite direction, 115 and fitting the adjacent winds together and to the lining as the winding progresses.

In testimony whereof I affix my signature in presence of two witnesses.
